CARTON MAKING MACHINE

Dennis Wood, Stanmore, England

Application November 16, 1936, Serial No. 111,115
In Great Britain November 18, 1935

4 Claims. (Cl. 93—79)

This invention relates to machines for making cartons of frusto-conical shape, from paper, cardboard or the like, subsequently impregnated with wax or other proofing material to render the 5 cartons liquid-tight.

The invention has for its object to provide an improved machine for making the frusto-conical bodies of the cartons in a continuous sequence of operations, starting from a web of paper or the 10 like, which, after printing, if desired, is cut to form the blanks, the edges of which are secured together by adhesive after rolling the blank around a conical mandrel or former.

According to this invention, the web of paper 15 or the like is fed to a series of cutting rollers, of which one pair make spaced incisions towards the two edges of the web, these incisions preferably diverging at equal angles to the line of travel, for producing the side edges of the blank from 20 which the carton is to be made, and a second pair make curved cuts transversely of the blank for producing the convex bottom edge and concave top edge of the blank, some or all of the 25 transverse cuts being made preferably across the entire width of the web so as to divide up the waste material.

Adhesive is applied to one of the side edges of the blank at a point between the two pairs of cutting rollers, that is, while the blank is still 30 connected to the web at front and rear; when the web is cut transversely, the blank or leading edge passes on to one or more supporting guide rollers before the next transverse cut is made, and the blank thus severed is carried forward 35 by these rollers on to a table or platform beneath a mandrel of frusto-conical shape, around which it is folded, a plurality of these mandrels being mounted upon a rotary standard or carrier, during the intermittent rotation of which the formation 40 of the carton body proceeds until it comes to a position for ejection.

The invention is hereafter described with reference to the accompanying drawings, in which:—

45 Fig. 1 is a side elevation of the carton-forming machine.

Fig. 2 is a plan view.

Fig. 3 is a plan of the cutting rollers on a larger scale.

50 Fig. 4 is a part sectional elevation of the cutting rollers.

Fig. 5 is a partial side elevation, seen in the opposite direction to Fig. 1, showing the mechanism for driving the gumming device.

55 Fig. 6 is an end view of Fig. 5.

Figs. 7 and 8 are two elevations at right angles to one another, showing the mechanism for folding the carton body around the mandrel.

Fig. 9 is a plan view of the folding mechanism.

Referring to Figs. 1 and 2, the web 10 of paper 5 or the like, drawn from a roll 11 provided with a brake 12, is passed over a tensioning roller 13 mounted on spring controlled levers 14, and over a guide roller 15, to a printing mechanism 16, from which it passes over another tensioning 10 roller 17 to a pair of feed rollers 18 in advance of the cutting rollers 19, 20. All these rollers are driven by suitable gearing 21, 22 from a vertical shaft 23, itself driven through bevel gearing 24 from a main shaft 25, which also drives the printing mechanism 16 through suitable gearing 26.

As shown in Fig. 3, the first cutting roller 19, having helical cutting blades 27, makes spaced incisions 28 towards the two edges of the web, these incisions diverging at equal angles to the 20 line of travel; for this purpose, the roller 19 has circumferential recesses 29 adjacent to its ends, in which recesses the helical cutting blades 27 are provided, the blades projecting beyond the circumference of the roller by the thickness of the 25 paper web, so that the blades produce the incisions 28 near the edges of the web, while the latter is gripped (see Fig. 4) between the cylindrical surfaces of this roller 19 and the lower roller 19a, which is plain. The second pair of 30 cutting rollers 20, 20a, having curved blades 30 on the upper roller 20, cut the web transversely as at 31 for producing the curved edges of the blank x, while the web is gripped (see Fig. 4) between the cylindrical surfaces of this roller 20 35 and the plain lower roller 20a; at the same time these cutting rollers 20, 20a sever the edges of the web 10 so as to divide up the waste material, for which purpose, the upper cutting roller 20 has its blades 30 (or alternate blades) extending 40 across to slightly beyond the width of the web, the developed shape of these blades 30 conforming to one of the curved edges of the required blank x. The blades may be shaped to cut the longer curved edges, i. e. the edges which represent the larger ends of the frusto-conical carton bodies, in which case both edges of the blanks will have the same curvature and the resulting carton bodies will be of greater height on one side than on the opposite side; to avoid this, the 45 roller 20 is provided with auxiliary cutting blades 32 of shorter length and sharper curvature than the blades 30, so that both the top edge and the bottom edge of the blank are cut to proper shape by removal of the narrow concavo-convex slip, 50 55

indicated at 33 in Fig. 3, and the resulting carton bodies will be of even height.

Between the two pairs of cutting rollers, adhesive is applied to the web along one side of an incision 28 made by the first pair of cutting rollers 19, 19a, so that the blank x is gummed whilst still connected to the web at front and rear; as shown in Figs. 2, 3 and 4, a tank 34 containing gum or other adhesive is mounted at the side of the machine, near to the second pair of cutting rollers 20, 20a. Within this tank a roller 35 is revolved, for example intermittently by means of a ratchet mechanism 36; blades or scrapers may be arranged at opposite sides of the roller, one in order to regulate the thickness of adhesive taken up by the roller 35, and the other in order to scrape the roller entirely clean so that a supply of fresh adhesive will always be available on the top of the roller. The adhesive is transferred to the blank by means of an oscillating arm 37, operated by a cam device 38, the arm being fitted at its extremity with a metal strip or pad 39 shaped to cover the area to be gummed on the blank; the under surface of the gumming strip or pad may be plain or may be ribbed or chequered to assist the retention of the adhesive taken from the roller 35. The fulcrum end of the arm 37 is forked to engage a horizontal pivot 41 upon a vertical sleeve 42 which is turned periodically by the cam 38, acting through a lever 43, link 44 and crank 45; the movement carries the pad 39 at the end of the arm from above the top of the gumming roller 35 (as in Fig. 2) to a position above the area to be coated with adhesive (as in Fig. 3), and vice versa. The arm 37 is raised clear during the forward and return movements by a horizontal rail or cam 46 engaging a roller 47 underneath the arm 37, this rail being fixed to a sleeve 48 slidable vertically on the post 49 which supports the other sleeve 42; a link 50 operated by a cam 51, through a bell crank 52, lifts the sleeve 48 and rail 46 during the swinging movements of the arm 37, but allows the arm to descend into contact with the roller 37 and the web 10 at the respective ends of its movement.

If the web in which the blank has been partly cut out is travelling continuously forward, the oscillating arm 37 may be made to travel in the same direction and at the same speed as the web during the gumming operation, thus avoiding any smearing of the adhesive; this movement may be produced by a cam 53 upon the same shaft 54, which causes the supporting post 49 of the gumming arm 37 to travel along parallel to the web 10, the post 49 being supported by two bars 55 slidable through guides 56, and operated by a link 57 attached to a cross head 58, as seen in Fig. 5.

The cutting rollers 19, 20 may however be given an intermittent movement, so that the adhesive can be applied by the oscillating arm 37 during the momentary stoppage of the web; the tensioning roller 17 will allow for this difference between the movement of the web through the printing mechanism 16 and its movement through the cutting rollers 19, 20.

When the web is cut transversely by the rollers 20, 20a, after the application of adhesive, the leading end of the severed blank has already passed between a pair of supporting and guiding rollers 59, leading to another pair 60, before the trailing edge of the same blank is severed from the web; the guide rollers 59, 60 are reduced in diameter towards their ends, as seen in Fig. 2,

so that the waste material from the outer edges of the web can drop down and escape past the thinner end-portions 61, 62 of the guide rollers into a chute 63, this waste material having been cut into short lengths by the transverse cut 31 taken across the whole width of the web. The blank x is however carried forward substantially in a horizontal direction over the rollers 59, 60, which pass it over a grid 64 on to a hinged platform 65, while the waste material slips under this grid into the chute; the blank is then moved forward by an oscillating finger 66 which brings it into position beneath a mandrel 67, where it is located by a pair of rocking guides 68 carried by the platform, these guides closing together so as to center the blank in relation to the mandrel 67. This mandrel is one of a plurality mounted radially upon a standard or carrier 69 rotatable on a vertical axis, and driven intermittently with a step by step motion through a Maltese-cross mechanism 70, 71 and reducing gear 72.

A portion of the platform 65, adjacent to the position at which the blank is located, is cut away to provide an opening 73 through which a folding mechanism operates for rolling the blank upwards around the mandrel 67. The folding mechanism, which is shown more clearly in Figs. 7 to 9, comprises a plate 74 normally lying flush with the platform 65 but pivoted thereto at 74', which lifts the blank at its center line and presses it against the underside of the mandrel 67, the plate rocking on its pivot to ensure even pressure, a pair of spaced arms 75 which then rise and fold the blank up the two sides of the mandrel into U-shape, as indicated in dotted lines in Fig. 8, and a second pair of arms 76 arranged outside the first pair, these second arms rising at the same time as the first pair 75 but proceeding higher and then coming together so as to complete the folding of the blank around the mandrel. The folding mechanism is operated by cams and levers working in combination, the second pair of arms 76 being preferably arranged to operate one slightly in advance of the other so as to ensure a smooth overlapping of the two edges of the blank, with the coated edge over the other edge.

As shown in Fig. 7, the cams 77 and 78 are mounted upon the shaft 54 extending transversely beneath the platform 65, these cams respectively operating two bell crank levers 79 and 80 which control three sliders 81, 82, 83 mounted on a fixed vertical guide rod 84; the upper slider 81, which is connected by links 86 to the underside of the platform 65, is also connected by a buffer device 87 to the middle slider 82 on the same guide rod, this middle slider being itself connected by links 88 to the bell crank 79. When the latter rocks, these two sliders rise together and cause the plate 74 to lift the blank up against the mandrel 67. The continued rise of the slider 82 then compresses the spring buffer 87 to hold the blank tightly against the underside of the mandrel, and brings the arms 75 upwards to fold the blank into U-shape, and at the same time the lower slider 83 operated by the bell crank 80 and links 85 causes the second pair of arms 76 to move up with the first pair; these two pairs of arms have a mutual engagement by means of rollers 186 on the first pair acting upon cam surfaces 187 on the second pair. When the first pair of arms 75 has reached its upper position, the continued rise of the second pair 76 causes their cams 187 to travel relatively to the 75

rollers 186 so that the arms of this second pair can come together and complete the folding movement, the cams 187 being so shaped that one arm 76 moves in advance of the other, as already mentioned, to ensure the proper overlapping of the gummed edge of the blank.

The same cam shaft 54 is conveniently employed for the operation of the finger 66 and rocking guides 68 which locate the blank beneath the mandrel 67; for this purpose the shaft is provided with a third cam 188 engaging the roller-fitted extremity of a lever 89 mounted on a rocking shaft 90 which carries a second lever 91 the free upper end of the latter engaging with a lug 92 secured on a slideable spindle 93 and also with the roller-fitted extremities of two arms 94. The spindle 93, which is guided in lugs 93' on the bottom of the platform 65, carries the oscillating finger 66 and is controlled by a spring 95 which acts to draw the blank on to the platform 65 after the finger has engaged behind the blank by the sliding of the spindle 93 backwards by the lever 91 while the platform is in the lowered position seen in Fig. 7; the arms 94 are secured 25 to the spindles 96 of the rocking guides 68 so that these guides can close together when the platform 65 reaches its level position after the blank is in place thereon.

The arms 75 are fitted with thin vertical blades 30 97 set slightly obliquely as seen in Figs. 8 and 9, and the arms 76 are fitted with thin blades 98 extending inwards sufficiently to pass over the top of the mandrel 67.

When the blank has been folded round the 35 mandrel, a heated pressure pad 99, controlled by cam-operated levers 100, descends between the edges of the blades 98 on to the seam or joint, the folding mechanism then retiring downwardly below the platform 65, and the mandrel 67 being moved on to the next operative position, 40 while the pressure pad 99 continues to hold the blank in place.

The number of mandrels 67 may be varied, but in the preferred construction illustrated, the rotatable standard or carrier 69 is provided with 45 eight mandrels spaced evenly around its axis and the periodical movements of the carrier shift these mandrels through 45 degrees in the horizontal plane; the intermittent motion can be obtained for example by the Maltese cross mechanism 70, 71, or by any other suitable means.

The mandrels 67 are preferably constructed in such a way that the pressure can be applied to the whole length of the seam, so as to ensure 55 a quick and sound joint, but where the carton bodies are to be provided with a step or flange to receive a sealing disc, as in the case of milk bottles, the mandrels are arranged to allow a portion of the conical folded blank or carton body 60 to be exposed for the inturning or rolling down of the narrow end of the body. The mandrels are therefore made with a hollow main portion, shorter than the carton body by the amount required for rolling or inturning, and an auxiliary 65 movable end-piece 101, making up the full length; this end-piece, which is pivoted at 102 at the base or larger end of the mandrel, is controlled for example by a push-rod 103 slideable through 70 the boss 104 and operated by a third lever 105 secured on the rocking shaft 90. The heated pressure pad 99 is also provided with a hinged section 106 at one end, this section being normally supported in line but being raised or temporarily removed (as hereafter described) to 75 expose the exterior of the narrow end of the car-

ton body at the same time and to the same extent as the exposure of the interior by the withdrawal of the end-piece 101 of the mandrel.

While the pressure pad remains firmly engaged with the whole length of the seam, the carrier rotates for example through four steps or half a revolution, each step bringing another mandrel 67 into position to receive a blank which is rolled round it by the same folding mechanism. At the fifth position, the movable end-piece 101 of 10 the mandrel is withdrawn by the push rod 103 and the hinged section 106 of the pressure pad 99 is removed by another push rod 107, so as to allow the rolling or inturning of the narrow end of the carton body at this position, by means of 15 grooved rollers 108 mounted in a rotary head 109, the advance of which operates the push rod 107 to remove the hinged section of the pressure pad. The rollers 108 act to turn or curl over the rim of the carton body so as to form a doubled- 20 over flange or beading, which is subsequently smoothed by a revolving punch or plunger 110 at the next position of the carrier 69, with or without forming a step inside the end of the carton. Just before the mandrel reaches the seventh position, the heated pressure pad 99 is 25 raised by the levers 100, the seam being now dried out, and at the seventh position a transfer arm 111 operates to strip the formed carton body from the mandrel 67, the carton falling on to a conveyor for example. 30

Preferably, however, the carton bodies are passed on to a sliding or rocking holder 112 having part-conical rests or receptacles for carton bodies which is oscillated in relation to the 35 movements of the forming machine, this holder being adapted to take two or more of the cartons in turn. When one carton has been placed in position upon one rest of the holder 112, and as the transfer arm 111 is retiring ready for 40 stripping the next carton off its mandrel, the holder 112 is displaced laterally so as to bring another rest or receptacle into position facing the next mandrel which is to deliver. After the holder 112 has received the two cartons, 45 the transfer arm 111 at its next stroke will push both these cartons at the same time into another machine in which the cartons are fitted with bottoms, either at their wider or at their narrower ends according to the kind of carton, 50 e. g. milk-bottles or cream-tubs. Thus the transfer arm 111, which is slidably operated by a link 114 from a lever 115 driven by a face cam, makes short and long strokes, short strokes for the first position of the rocking holder 112 and a 55 long stroke for the other position of the holder, in which the laterally displaced carton body is pushed into the drum by an auxiliary transfer arm moving in synchronism with the first. After the bottoms have been fitted in the carton bodies, 60 the latter are impregnated with wax or other proofing material, being then ready for filling and subsequent capping by means for example of a sealing disc pressed into place upon the internal step formed by the plunger after the 65 inturning of the narrow end of the carton body in the machine above described.

What I claim is:—

1. A machine for making frusto-conical carton bodies, comprising cutting rollers, means for 70 feeding a web of material through said cutting rollers, said cutting rollers adapted to make pairs of incisions in said web of material and subsequently to cut said web transversely, said pairs of incisions being spaced along said web and 75

the incisions of each pair being equally inclined to the line of travel of said web through said rollers, said transverse cuts being curved to intersect corresponding ends of said pairs of incisions, means for applying an adhesive to said web adjacent to one incision of each pair prior to the making of said transverse cuts, means for folding the blank defined by the intersection of said transverse cuts and incisions into frusto-conical shape with an overlap containing said adhesive, and means for pressing said overlap to secure adhesion.

2. A machine for making frusto-conical carton bodies, comprising a pair of co-operating rollers, helically disposed cutting blades upon one of said rollers, a second pair of co-operating rollers, at least one curved cutting blade upon one of the second-mentioned rollers, means for feeding a web of material through said pairs of co-operating rollers in turn, the first-mentioned rollers producing pairs of straight incisions towards the opposite edges of said web, at least one incision of each pair being inclined to the line of travel of said web, the second-mentioned rollers producing transverse cuts intersecting said pairs of straight incisions in said web, means for applying an adhesive to said web adjacent to one incision of each pair, said adhesive applying means being located between the first mentioned rollers and the second mentioned rollers, means for folding the blank defined by the intersection of said transverse cuts and incisions into frusto-conical shape with an overlap containing said adhesive, and means for pressing said overlap to secure adhesion.

3. A machine for making frusto-conical carton bodies, comprising cutting rollers, means for feeding a web of material through said rollers, said rollers cutting out blanks of annular sector shape from said material, means for applying adhesive to said web at a position corresponding to a straight edge of the blank to be produced by said cutting rollers, a platform, a plate pivoted in said platform and normally flush therewith, means for passing the blanks in turn upon said platform, a mandrel of frusto-conical shape lo-

cated above said platform, means for lifting said platform to raise a blank against the lower side of said mandrel, said pivoted plate then rocking to an inclined position parallel to the lower generatrix of said mandrel, a pair of arms adapted to rise through said platform on opposite sides of said plate and to fold said blank into U-shape, a second pair of arms adapted to rise through said platform on opposite sides of said plate outside the first mentioned pair of arms and to come together for folding the ends of the U-shaped blank around said mandrel, and means for pressing said edges into contact to secure adhesion.

4. A machine for making frusto-conical carton bodies, comprising cutting rollers, means for feeding a web of material through said rollers, said rollers cutting out blanks of annular sector shape from said material, means for applying adhesive to said web at a position corresponding to a straight edge of the blank to be produced by said cutting rollers, a platform, means for passing the blanks in turn upon said platform, a rotatable standard, means for driving said standard in intermittent rotation, a plurality of frusto-conical mandrels mounted radially upon said standard, each of said mandrels arriving in turn above said platform during the intermittent rotation of said standard, means for lifting the blank located upon said platform into contact with the mandrel located above said platform, means for folding the edges of said blank around said mandrel, means for pressing said edges into contact to secure adhesion, said pressing means including a removable part adapted to engage one of said edges at the narrow end of the folded blank and remaining partly operative during a substantial part of the rotation of said standard, means for inturning the narrow end of the folded blank in a subsequent position of said mandrel, and means for removing said removable part of said pressing means to inoperative position during the operation of said inturning means.

DENNIS WOOD. 45
